TOILET DEVICE

Morton M. Rosenfeld, Mount Vernon, N.Y.
(271 Madison Ave., New York, N.Y.)
Filed Oct. 6, 1961, Ser. No. 143,361
7 Claims. (Cl. 4—90)

This invention relates to a toilet device, and more particularly, to a toilet particularly adapted for use in an underground structure such as a bombshelter.

There is a need for a simple toilet device for bombshelters and the like wherein there is a lack of a water supply for flushing the same. Accordingly, a toilet device must be provided which may be flushed without the use of an automatic water supply. Also, a toilet device should be provided with some means to prevent noxious vapors from entering the room in which the toilet device is located.

In accordance with the present invention, a toilet device is illustrated as being installed in a bombshelter which is preferably an underground structure. The toilet device is mounted on one of the walls partially defining the bombshelter and is connected to a pipe extending through said one wall. The end of the pipe remote from the toilet device is in communication with a waste receiving tank or the like. The toilet device is provided with a pivotably mounted cover having a reciprocably mounted plunger tube disposed therein. The inner surface of the bowl may be cleaned by means of reciprocation of the plunger tube and the introduction of liquids into the bowl by means of the plunger tube which is hollow. Means are provided to sealingly secure the cover to the bowl and to selectively seal the passage through the plunger tube.

It is an object of the present invention to provide a novel toilet device.

It is another object of the present invention to provide a novel toilet device particularly adapted for use in bombshelters or the like.

It is another object of the present invention to provide a toilet device which is in communication with a waste disposal tank and does not have a supply of water or other flushing liquid connected thereto.

It is another object of the present invention to provide a toilet device with a means for causing waste material to be removed therefrom and conveyed to a waste disposal tank without the use of a water supply connected to said toilet device.

Other objects will appear hereinafter.

For the purpose of illustrating the invention there is shown in the drawing a form which is presently preferred; it being understood, however, that this invention is not limited to the precise arrangements and instrumentalities shown.

FIGURE 1 is a partial perspective view of an underground bombshelter with the toilet device supported by one of the walls of the bombshelter.

FIGURE 2 is a sectional view of the toilet device illustrated in FIGURE 1.

Referring to the drawing in detail, wherein like numerals indicate like elements, there is shown in FIGURE 1 a bombshelter designated generally as 10.

The bombshelter 10 includes a floor 12, a wall 14 which is upright with respect to the floor 12, a wall 16 and a wall 20. The walls 14, 16 and 20 partially define the enclosure of the bombshelter. A wall 18 is disposed parallel to the walls 16 and 20 and defines a passageway therebetween through which persons may gain access to the doorway 22.

The passageway between the walls 18 and 20 is provided with a hollow floor 24. An impervious bag or other waterproof means may be provided within the hollow

2

floor 24 so that a supply of water may be disposed therein. The water may be removed from within the hollow floor 24 by means of a manual pump 26. The pump 26 is supported on the wall 20 and is provided with an inlet end which extends into the enclosure defined by the hollow floor 24. A step 25 is provided in the doorway 22 because of the difference in height between the hollow floor 24 and the floor 12 of the bombshelter 10.

A hollow waste receiving tank 28 is mounted between the walls 16 and 18. The tank 28 is of sufficient size so that it extends between the doorway 22 and the wall 14. The tank 28 is provided with a vent pipe 30 which is adapted to extend to a point above ground level. A pipe 32 extends through the wall 16. One end of the pipe 32 is in communication with the interior of the tank 28. The other end of the pipe 32 is removably connected to a toilet device 34.

As shown more clearly in FIGURE 2, the toilet device 34 includes a generally semi-spherical bowl 36 having a conduit 38 tangentially disposed with respect to a bottom portion thereof. The conduit 38 is hollow and provides communication between the bowl 36 and the pipe 32. The bowl 36 is provided with a radially outwardly extending flange 40 having a groove thereon for receiving a portion of an O-ring 41.

The O-ring 41 is secured to a flange 44 on a generally semi-spherical cover 42. The flange 44 is provided with a handle 46 which facilitates separating the cover 42 from the bowl 36. The cover 42 is pivotably secured to the flange 40 on the bowl 36 by means of a hinge 48.

A bore 50 extends through the cover 42 and a depending boss 52. The bore 50 is in alignment with the intersection of the conduit 38 and the bowl 36. A hollow plunger tube 54 is reciprocably disposed within the bore 50. The upper end of the tube 54 projects beyond the periphery of the cover 42 and terminates in a flared portion 56 simulating a funnel. The upper end of the bore in the tube 54 is selectively closed by means of a screw or cork stopper 55 so as to prevent vapors from passing therethrough.

The lower end of the tube 54 extends to a point adjacent the bottom of the bowl 36. The lower end of the tube 54 is provided with a threaded reduced diameter portion which extends through a central aperture in a dish shaped flexible member 58. The member 58 is retained on the tube 54 by means of a removable lock nut 60. In the lowermost position of the tube 54, the periphery of the member 58 engages the inner peripheral surface of the bowl 36. The member 58 is preferably made from a non-corrosive flexible material such as rubber, polyethylene, etc. The member 58 is sufficiently flexible so that the nut 60 may approach the bottom of the bowl 36 with the periphery of the member 58 being deformed and in engagement with the inner peripheral surface of the bowl 36.

The present invention is utilized as follows:

When it is necessary to use the bombshelter 10, access may be gained by the passageway between walls 18 and 20 and the doorway 22. When the toilet device 34 is not in use, the respective elements thereof will be in the position illustrated in FIGURES 1 and 2. When it is desired to make use of the toilet device 34, the cover 42 may be pivoted in a counter clockwise direction in FIGURE 2 by applying pressure on the handle 46. The hinge 48 enables the cover 42 to rotate through an arc of approximately 180°. Liquid excrement introduced into the bowl 36 readily flows through the conduit 38 into the tank 28. Before solid excrement is introduced into the bowl 36, the inner peripheral surface of the bowl 36 is preferably wetted by pouring a small amount of water thereon.

The solid excrement may be caused to move from the

bowl 36 through the conduit 38 and the inner peripheral surface of the bowl 36 may be cleaned by manipulation of the plunger tube 54. The cover 42 is first moved to the solid line position illustrated in FIGURE 2. Thereafter, the cork stopper 55 is removed and liquid may be poured through the tube 54. At approximately the same time, the tube 54 may be reciprocated so that the member 58 is deformed by engagement with the inner peripheral surface of the bowl 36 thereby cleaning said surface. The cleaning of the inner peripheral surface of the bowl 36 is facilitated by the flow of water or other liquid introduced into the bowl 36 by way of the hollow tube 54. If water is utilized to flush the bowl 36, said water may be obtained from the hollow floor 24 by means of the pump 26. The water may be conveyed from the pump 26 to the bowl 36 in any convenient container.

The O-ring 41 provides a gas tight seal between the cover 42 and the bowl 36. The cork stopper 55 will be applied in the bore of the tube 54 thereby preventing escape of noxious vapors into the bombshelter 10. The tank 28 may be provided with a vent pipe 30 so that noxious vapors may escape to the atmosphere and prevent gases from building up the pressure within the tank 28. The tank 28 may contain chemicals of the type generally utilized in septic tanks and the like. If desired, the tank 28 may be provided with an overflow pipe which is connected to a sewer, a leeching field, etc.

The tank 28 need not be in the bombshelter 10, but may be adjacent an outside wall thereof or integral with an outside wall of the bombshelter. It is within the scope of the present invention to mount the toilet device on the tank 28 so that they may be installed as a unit. If desired, the upper end of the plunger tube 54 may be provided with a container of a flushing liquid which is dispensed each time the tube 54 is reciprocated upwardly. Such dispensing may be accomplished by means of a check valve. Alternatively, the upper end of tube 54 may be threaded so that one end of a hose may be connected thereto with the other end of the hose being connected to a source of liquid under pressure.

When the tank 28 is located as illustrated, its upper surface may be utilized as a bench or supporting surface for a variety of purposes. When the toilet device is connected directly to the tank, it should be removably secured thereto or disposed in well in the top wall of tank 28 so that the top wall may still be utilized as a supporting surface.

Thus, it will be seen that I have provided a novel toilet device which does not require a supply of water to be connected thereto for flushing the same. While the toilet device 34 has been illustrated in a bombshelter 10, it will be appreciated that the same may be utilized on boats, in cottages, camps, etc.

The present invention may be embodied in other specific forms without departing from the spirit or essential attributes thereof and, accordingly, reference should be made to the appended claims, rather than to the foregoing specification as indicating the scope of the invention.

I claim:

1. A toilet device comprising a bowl, an outlet conduit in communication with said bowl, a cover movably mounted on said bowl, a plunger reciprocally mounted through said cover, said plunger having a flexible member on one end for engagement with the inner peripheral surface of said bowl.

10 2. A toilet device in accordance with claim 1 wherein said plunger is provided with a longitudinally extending bore therethrough, and means for selectively closing said bore.

15 3. A toilet device in accordance with claim 2 wherein said means for selectively closing said bore is a cork stopper.

20 4. A toilet device in accordance with claim 2 wherein the other end of said plunger is funnel-shaped.

25 5. A toilet device in accordance with claim 2 wherein said flexible member is dish-shaped, and includes means removably securing said flexible member to said one end of said plunger.

30 6. A toilet device comprising a bowl, an outlet conduit tangentially disposed with respect to said bowl, a cover pivotably secured to said bowl, a plunger reciprocably mounted in said cover, the longitudinal axis of said plunger being directed toward said inner section of said bowl and said conduit, and a flexible member removably secured to one end of said plunger, said member being larger than said conduit, said plunger having a length sufficient so that said flexible member may be in engagement with the inner peripheral surface of said bowl.

35 7. A toilet device in accordance with claim 6 wherein said plunger is provided with a longitudinally extending bore therethrough, and including selectively operable means for closing said bore so as to prevent passage of fluids through said bore.
